UNITED STATES PATENT OFFICE.

JOHN MERRY, OF NEWARK, NEW JERSEY, ASSIGNOR TO THE BIGELOW
CARPET COMPANY, OF MASSACHUSETTS.

DESIGN FOR CARPET.

SPECIFICATION forming part of Design No. 27,581, dated August 24, 1897.

Application filed July 7, 1897. Serial No. 643,764. Term of patent 3½ years.

To all whom it may concern:

Be it known that I, JOHN MERRY, a citizen of the United States, and a resident of Newark, in the county of Essex and State of New Jersey, have invented a new and original Design for a Carpet, of which the following is a specification.

This invention comprises a design for a carpet; and I do hereby declare that the drawing accompanying this specification conveys to any one a clear understanding of the same and is sufficient to enable such person to use my invention.

The design is characterized by a panel of clusters of flower forms and connecting festoons of flower forms and parallel panels of conventional figures and stemwork. 15

What I claim, and desire to secure by Letters Patent, is—

The design for a carpet, substantially as 20 shown.

In testimony whereof I have signed my name to this specification in the presence of two subscribing witnesses.

JOHN MERRY.
